UNITED STATES PATENT OFFICE.

HENRY A. ZIOLA, OF TOLEDO, OHIO, ASSIGNOR TO THE SWAETZBAUGH MANUFACTURING CO., OF TOLEDO, OHIO, A CORPORATION.

DESIGN FOR AN ELECTRIC GRIDDLE.

Application filed March 3, 1928. Serial No. 25,658. Term of patent 3½ years.

To all whom it may concern:

Be it known that I, HENRY A. ZIOLA, a citizen of Austria, residing at Toledo, in the county of Lucas and State of Ohio, have invented a new, original, and ornamental Design for Electric Griddle, of which the following is a specification, reference being had to the accompanying drawing, forming a part thereof, in which:—

The figure is a front perspective view of an

electric griddle embodying the design of the invention.

I regard as a dominating feature the sunken surface joined in with the rim by the curved walls.

I claim:

The ornamental design for an electric griddle as shown and described.

HENRY A. ZIOLA.
